[57] **ABSTRACT**
A circuit for initially applying an unusually large drive voltage to a solenoid coil and for subsequently reducing the applied voltage during the travel of the solenoid plunger. The solenoid coil is serially connected to a first transistor circuit operating as an on-off switch and also is serially connected to a second transistor circuit operating to variably control the voltage applied to the solenoid. A capacitor-charge timing circuit controls the variable transistor and thereby gradually reduces the voltage applied to the solenoid.

SOLENOID DRIVE CIRCUIT

BACKGROUND OF THE INVENTION

This invention relates to electromechanical control systems and more particularly relates to an electronic circuit for applying a desired voltage waveform to a solenoid coil.

The solenoid is an old and well established electromechanical device. It is used in diverse applications for changing electrical energy to mechanical energy. For example, I am interested primarily in the uses of solenoids for operating an input-output typewriter in response to remotely originated electrical signals in the manner disclosed in my copending application, Ser. No., 79,202, filed Oct. 8, 1970, for "Input-Output Typewriter Apparatus," by Edwin E. Mason, and assigned to the same assignee as the instant application.

The conventional manner of operating a solenoid is to apply to the solenoid a voltage which is slightly larger than or equal to the minimum voltage necessary to actuate the solenoid. Usually this voltage is continuously applied to the solenoid until the solenoid is de-energized. To deenergize a solenoid, the voltage is lowered to a value below the minimum holding voltage and ordinarily to zero volts.

There are several undesirable consequences of this conventional operation which my invention overcomes. With all solenoids, a minimum actuation voltage is necessary to overcome the inertia of the solenoid and to begin the movement of its plunger. However, with the continued application of the same voltage, the plunger will accelerate until its travel is abruptly ended by a mechanical stop. At the instant the plunger strikes the mechanical stop, it is traveling at its maximum velocity and consequently has its maximum momentum. The sudden stopping of the plunger produces a sudden slamming or hammering of the plunger into the mechanical parts of the solenoid. This hard slamming of the plunger tends to jar all the equipment with which the solenoid is associated and in particular tends to weaken, wear, and eventually damage the solenoid.

Because a lower voltage can be utilized to hold the solenoid in its actuated position after the plunger comes to rest, the continued application of the higher actuation voltage functions only to waste electrical power and to cause the dissipation of excess heat into the associated equipment.

There is a need therefore, for a solenoid drive circuit which will initially overdrive the solenoid by applying a voltage to the solenoid which is considerably greater than its minimum actuation voltage. This will hasten the change in momentum of the plunger and similarly will more rapidly raise the solenoid current to the actuating current by more quickly overcoming the high initial reactance of the solenoid. There is also a need for a circuit which will automatically reduce the voltage applied to the solenoid during the plunger travel after the solenoid current has risen to a desired value, and yet will continue to maintain the solenoid current slightly above or equal to the minimum holding current of the solenoid.

SUMMARY OF THE INVENTION

The invention is a solenoid drive circuit for energizing and for de-energizing a solenoid in response to suitable signals at a drive circuit input. The solenoid drive circuit has a first electronic switch means which is in series with a solenoid and a source of driving electrical power. The first electronic switch means switches the current to the solenoid and includes the drive circuit input at which the first electronic switch is controlled.

An electronic control valve means is also connected in series with the solenoid at one solenoid terminal and is used for variably controlling a portion of the current to the solenoid. The electronic valve means also has a control input. A holding current conducting means, such as a resistor, is connected parallel to the valve means to permit a minimum holding current to flow through the solenoid, bypassing the valve means.

A timing means is provided for providing a time changing current for controlling the valve means. The timing means

comprises serially connected timing resistance, capacitance and a diode connected to permit current flow charging the capacitance. The timing means is connected between the control input of the valve means and the other solenoid terminal.

5 Discharge means for discharging the capacitance is also provided. The discharge means comprises a serially connected dissipating resistance and a second electronic switch means connected across the capacitance. The control input of the second electronic switch is connected to have at least the voltage across the diode applied to the control input of the second electronic switch.

OBJECTS OF THE INVENTION

15 It is an object of the invention to provide an improved solenoid drive circuit.

Another object of the invention is to provide a solenoid drive circuit which will initially overdrive the solenoid until the solenoid is driven at approximately its minimum holding current.

20 Another object of the invention is to speed up the actuation and complete operation of a solenoid and at the same time reduce the momentum of the solenoid plunger as it arrives at its actuated position.

25 Another object of the invention is to provide a solenoid drive circuit which will exhibit an improved duty cycle so that solenoid operation may be improved while heat generation and power losses are minimized.

30 Further objects and features of the invention will be apparent from the following specification and claims when considered in connection with the accompanying drawings illustrating the invention.

DESCRIPTION OF THE DRAWINGS

35 FIG. 1 is a schematic view of the preferred embodiment of the invention; and

FIG. 2 is a graph illustrating solenoid voltage and current during operation of the solenoid.

40 In describing the preferred embodiment of the invention illustrated in the drawings, specific terminology will be resorted to for the sake of clarity. However, it is not intended to be limited to the specific terms so elected and it is to be understood that each specific term includes all technical equivalents which operates in a similar manner to accomplish a similar purpose.

DETAILED DESCRIPTION

50 The preferred embodiment of the invention is illustrated in FIG. 1. The solenoid 10 is to be controlled by the remainder of the circuit which receives its driving power from a source at the terminals 12 and 14. The circuitry of the section 16 outlined in broken lines is simply a carlington pair connected and operated as a first electronic switch means 16. The electronic switch means 16 includes and is controlled at its drive circuit input 18. It is intended that the drive circuit be digitally controlled and therefore no current will flow through the darlington pair when the input is at zero volts while current can flow through the darlington pair when the input voltage is at the suitable positive voltage. Thus the electronic switch 16 is closed when zero volts is applied at the input terminal 18 and is opened when a positive voltage is applied at the terminal 18.

55 The function therefore, of the electronic switch 16, is to switch the current through the solenoid 10.

60 The solenoid 10 is also serially connected to an electronic valve means which, in the embodiment illustrated in FIG. 1, is the bipolar transistor Q₄. Transistor Q₄ is connected in a common emitter configuration and has a control input at its base terminal 20. The purpose of the transistor Q₄ is to variably control a portion of the solenoid current. It will become obvious that many other electronic valve means could be used in place of Q₄ and specifically a field effect transistor may be highly desirable in some applications.

65

70

75

A resistor R_7 is connected to bypass solenoid current around Q_4 and therefore is connected parallel to the valve means Q_4 . The purpose of the resistor R_7 is to permit a minimum holding current to flow through the solenoid 10 when the transistor Q_4 is not conducting.

The preferred value of the resistor R_7 in the circuit illustrated in FIG. 1 is 220 ohms at 3 watts. The important fact is that the value is selected in order to provide the minimum holding current and therefore the value of R_7 is approximately equal to $E_{cc}/I_m \cdot R_s$, where R_s is the solenoid DC resistance, E_{cc} is the voltage of the source of power at the terminals 12 and 14, and I_m is the minimum solenoid holding current.

The electronic valve transistor Q_4 is controlled by a timing means indicated generally as 30. The timing means comprises a serially connected timing resistance R_5 , a capacitance C_1 and a diode D_1 which is connected at a polarity to permit current flow charging the capacitor. This series connected timing means is connected between the control input at the base 20 of transistor Q_4 and the terminal of the solenoid to which Q_4 is not connected. The function of the timing means 30 is to provide a time changing current for controlling the valve means transistor Q_4 . The charging circuit of the timing means 30 is through the base-emitter junction of the transistor Q_4 , through the series connected timing means 30 and through the electronic switch 16. A leakage resistor R_6 is connected between the base 20 of the transistor Q_4 and the power source terminal 12 in order to provide a path for leakage current through the base when the transistor Q_4 is cut off.

As will be seen below, the capacitor C_1 charges during the excitation of the solenoid 10 and must be discharged when the solenoid 10 is de-energized. For this purpose a capacitance discharge means 31 is provided by a series connected resistor R_4 and a second electronic switch in the form of the transistor Q_3 . These are connected across the capacitance C_1 so that when the transistor Q_3 is conducting the capacitance C_1 will be discharged. The base of the transistor Q_3 , which functions as the control input of this second electronic switch, is connected to have at least the voltage appearing across the diode applied to the base of the transistor Q_3 . In the preferred circuit the capacitor C_1 and the diode D_1 share a common node 34 to which the emitter of the transistor Q_3 is connected. The base is connected to the opposite side of the diode D_1 so that the diode voltage appears at the base to emitter input of the transistor Q_3 .

OPERATION

Referring now to FIGS. 1 and 2, we may assume that operation begins with the solenoid de-energized and with zero volts appearing at the input 18 so that no current is flowing through the electronic switch 16. We shall assume also that the capacitor C_1 is fully discharged.

When an input signal appears at the input terminal 18 in the form of a positive step function, the darlington pair of the electronic switch 16 will begin conducting. Immediately, as illustrated at time zero in FIG. 2, the voltage across the solenoid will be substantially the power supply voltage at the terminals 12 and 14 (more exactly it will be less by the sum of the emitter-collector voltages of transistors Q_2 and Q_4). For purposes of illustration we have selected this voltage V_1 as 40 volts. The positive input signal voltage will continue at the input 18 so long as it is desired to hold the solenoid in an energized position. The current i_s in the solenoid 10 (shown in FIG. 2) will begin to increase in approximately the ordinary exponential manner. Simultaneously, current will begin flowing through the emitter-base junction of the transistor Q_4 and through the timing means 30 and will begin charging the capacitor C_1 . Eventually, for example at T_2 in FIG. 2, the capacitor will be fully charged such that base current no longer flows in transistor Q_4 . At this point transistor Q_4 will cease conducting and the voltage on the solenoid will be substantially reduced to a minimum holding level, for example, V_4 illustrated in FIG. 2. Only a minimum holding current will be flowing through the solenoid and through the resistor R_7 .

All during the time these things were happening, the voltage on the diode D_1 will have caused the diode to be forward biased and therefore will maintain the discharging transistor Q_3 in a nonconducting state. As long as the appropriate positive input appears at the terminal 18, the solenoid will remain energized with the minimum holding current flowing through it.

In some solenoid applications there is no need to hold the solenoid plunger in its actuated position. Often a designer desires only to actuate the plunger and then immediately return it to the de-energized position. Such operation is easily accomplished while maintaining the advantages of this invention. The holding current resistance R_7 is merely eliminated from the circuit. Removal of this current path which is parallel to the valve means of transistor Q_4 eliminates any holding current. Theoretically, R_7 is made to have infinite value to provide zero holding current. With this modification, the voltage applied to the solenoid will taper to zero volts instead of to a minimum holding voltage, and the solenoid current will similarly taper to zero amps. The solenoid will be smoothly actuated and then the plunger will return to the de-energized position when the solenoid current tapers below the minimum holding current. The time this takes and the voltage and current taper can be selected by design as described below.

If now the input voltage is reduced to zero, current will no longer be able to flow through the solenoid 10 from the power supply at the terminals 12 and 14. At this instant of time indicated as T_3 , in FIG. 2, the magnetic field of the solenoid will begin to collapse and the voltage polarity of the solenoid will reverse. The reversed solenoid voltage will be applied in a back biased direction across the diode D_1 and will therefore immediately turn on the transistor Q_3 and permit quick discharging of the capacitor C_1 . This will continue until the energy stored in the solenoid 10 and in the capacitance C_1 is completely dissipated in the resistances of the circuit. At that point the circuit has returned to its initial de-energized condition.

Referring now to FIG. 2 it is obvious that the time constant of the timing circuit 30 can be controlled and therefore proper circuit design permits selection of a different variety of waveforms and duty cycle conditions on the solenoid 10.

If, for example, R_5 is made relatively small to provide a shorter time constant and if R_6 is chosen so that, at the beginning of capacitor C_1 charging, the transistor begins operating well in the conducting region way above the transistor linear region, then a waveform like that indicated as V_2 in FIG. 2 will be provided.

If R_5 is made relatively large for a longer time constant to produce a nearly linear ramp function, and if R_6 is made such that capacitor C_1 charge begins with the transistor operation on the edge of the linear region, a drive voltage like V_3 will occur.

Of course a continuous family of solenoid drive voltage waveforms exists. A designer can select the waveform which meets the mechanical and the electrical characteristics of the solenoid. For example, a quicker acting, lower momentum solenoid would utilize a waveform like V_4 .

The circuit values are also chosen with a consideration of the time needed for the plunger of the solenoid to complete its travel. Solenoid travel could end at T_1 , T_2 , or T_4 , although I prefer it end near time T_2 . For example, in the preferred circuit illustrated, a time in the range of 8 to 14 milliseconds as T_2 has given desirable results.

The improved results of the invention become even more advantageous when used with devices such as a computer operated typewriter. Such a typewriter will be operated as rapidly as possible. This means that the solenoids will average relatively brief periods of time between operations. This also means that rapid movement of the solenoid plunger is extremely important. Hence, speed and low power loss become far more significant. The high initial voltage V_1 , which may be twice the minimum actuation voltage, may be applied to speed the plunger movement and yet this will not damage the solenoid coil because a much lower than minimum voltage is applied during the remainder of the actuation period.

It is to be understood that while the detailed drawings and specific examples given describe preferred embodiments of my invention, they are for the purposes of illustration only, that the apparatus of the invention is not limited to the precise details and conditions disclosed and that various changes may be made therein without departing from the spirit of the invention which is defined by the following claims.

What is claimed is:

1. A solenoid drive circuit for energizing and de-energizing a solenoid in response to suitable signals at a drive circuit input, said circuit comprising:
  - a. a first electronic switch means in series with said solenoid and a source of driving power, for switching current through the solenoid, the first switch means including and being controlled at said drive circuit input;
  - b. an electronic valve means connected in series with the solenoid at one solenoid terminal for variably controlling a portion of the current through said solenoid, the valve means having a control input;
  - c. a timing means for providing a time changing current for controlling said valve means and comprising serially connected timing resistance, capacitance, and a diode connected to permit current flow charging the capacitance, said timing means connected between the control input of said valve means and a source of d.c. electrical power; and
  - d. capacitance discharge means for at times discharging the capacitance and comprising a second electronic switch means connected across said capacitance, the control input of the second electronic switch means connected to have at least the voltage across said diode applied to the control input of the second electronic switch means.
2. A solenoid drive circuit according to claim 1 wherein said source of d.c. electrical power is at the other solenoid terminal and a dissipating resistance is serially connected to said second electronic switch.
3. A circuit according to claim 2 wherein there is provided a holding current conducting means, connected parallel to said valve means for permitting a minimum holding current to flow through the solenoid, bypassing the valve means.
4. A drive circuit according to claim 2 wherein an input re-

sistance is connected across the input terminals of said valve means.

5. A drive circuit according to claim 4 wherein the valve means is a field effect transistor having its gate connected to said charging circuit and the charging current flows substantially through said input resistance.
6. A drive circuit according to claim 2 wherein the valve means comprises a bipolar transistor connected in a common emitter configuration and wherein the timing circuit charging current is substantially emitter-base current of said bipolar transistor.
7. A drive circuit according to claim 2 wherein
  - a. said series capacitance and diode share a common node; and
  - b. said second electronic switch is a transistor having its common terminal connected to said common node and its input terminal connected to the opposite side of the diode.
8. A drive circuit according to claim 7 wherein
  - a. the valve means comprises a bipolar transistor connected in a common emitter configuration and wherein the timing circuit charging current is substantially emitter base current of said bipolar transistor;
  - b. a leakage resistance is connected between the emitter and base terminals of said bipolar transistor; and
  - c. a holding current conducting means is connected parallel to said valve means for permitting a minimum holding current to flow through the solenoid by passing the valve means.
9. A circuit according to claim 8 wherein
  - a. said first electronic switch means is a darlington amplifier connected between a common terminal of said power supply and said solenoid; and
  - b. said holding current conducting means is a resistor having a resistance approximately equal to $E_{cc}/I_{min} - R_s$ where R_s is the solenoid d.c. resistance, E_{cc} is the voltage of said source and I_{min} is the minimum solenoid holding current.
10. A circuit according to claim 9 wherein said timing capacitance is approximately in the range of 1 microfarad to 4 microfarads and said timing resistance is approximately 2200 ohms.
